UNITED STATES PATENT OFFICE.

ANSON C. MILLS, OF JACKSON, MICHIGAN.

FISH-STRINGER.

No. 849,410.

Specification of Letters Patent.

Patented April 9, 1907.

Application filed May 28, 1906. Serial No. 319,122.

To all whom it may concern:

Be it known that I, ANSON C. MILLS, a citizen of the United States, residing at Jackson, in the county of Jackson and State of Michigan, have invented certain new and useful Improvements in Fish-Stringers; and I do hereby declare the following to be a full, clear, and exact description of the invention, such as will enable others skilled in the art to 10 which it appertains to make and use the same.

My invention relates to improvements in fish-stringers; and its object is to provide a convenient device adapted to be attached to 15 the gunwale of a boat and provided with means for securely holding the fish and trailing the same over the side of the boat; and it consists, essentially, of a clamp adapted to be detachably secured to the boat and provided 20 with sockets and a needle detachably inserted in the sockets, and a cord attached to the needle by means of a globular head and hinged joint, as hereinafter more fully described, and particularly pointed out in the 25 claims, reference being had to the accompanying drawings, in which—

Figure 1 is an elevation showing my device attached to a boat for use; Fig. 2, an enlarged detail of the same, showing a portion 30 of the gunwale of the boat in section; Figs. 3 and 4, still further enlarged details, showing the method of attaching the cord to the needle.

Like numbers refer to like parts in all of 35 the figures.

1 represents a metal clamp adapted to be secured to the gunwale of a boat and provided at its outer end with sockets 2, adapted to detachably hold the needle 3.

4 represents a globular and slotted head 40 pivoted to the needle.

5 is a cord attached to the head, on which cord the fish are strung.

6 is an eye at the upper end of the needle, in which is a pivot to hold the head. 45

The parts of the head at each side of the slot are connected by a connecting member having a socket 7 at one side, in which socket is a knot 8 on the end of the cord to hold the same in the socket. 50

From the foregoing description the mode of operation of my device is obvious without further explanation.

What I claim is—

1. A fish-stringer, comprising a clamp having a socket, a needle detachably inserted in the socket, a pivoted head on the needle, and a cord attached to the head. 55

2. A fish-stringer, comprising a needle, a divided head pivoted to the needle and provided with a socket, and a cord having a knot within the socket. 60

3. A fish-stringer, comprising a needle having an eye at one end, a globular head having a transverse slot to receive the eye of the 65 needle and pivoted thereto and also provided with a socket, and a cord inserted in the socket and having a knot in the end within the socket.

In testimony whereof I affix my signature 70 in presence of two witnesses.

ANSON C. MILLS.
